GEARED HOIST

Fred P. Porter, Kellogg, Idaho, assignor to Coeur D'Alene Hardware & Foundry Company, Wallace, Idaho, a corporation of Idaho

Application April 15, 1935, Serial No. 16,473

4 Claims. (Cl. 254—186)

This invention relates to improvements in the class of pushing and pulling implements, and its objects are as follows:—

First, to provide a hoist which includes a single hoisting drum with a pair of integral, thickened end flanges, each of which has a co-acting brake mechanism, and one of which has an internal gear capable of operation by drive means.

Second, to provide a hoist in which the driven gear, whether internal or external, the two end flanges and the hoisting drum are an integral structure, either actually or functionally, so as to reduce the drum to the utmost simplicity as well as to insure its absolute ruggedness and durability, both end flanges being thickened so as to enable their use as braking surfaces in order to further the desired simplicity.

Third, to confine the support of the hoisting drum to roller or other bearings which run on races attached to a shaft which is made stationary by virtue of being secured to a pair of end plates, the removal of the end plates from the foundation and the removal of the shaft from the end plates enabling an almost immediate separation of the hoisting drum from the rest of the mechanism.

Fourth, to provide a hoist which is confined to so few major parts that it is capable of ready transportation into regions which would be impenetrable and totally inaccessible to similar contrivances of a more complex nature.

Fifth, to utilize the foregoing hoisting drum for the purpose of a duplex braking system, there being an independent brake for each of the thickened flanges, one being foot-operated for periodical stopping of the drum as in service, the other being hand-operated and of a construction to enable permanent locking of the drum in a stopped position, the details of the braking system being claimed in a division of this application filed by Fred P. Porter, March 3, 1936, Serial No. 66924.

Sixth, to provide a unitary hoist which is self-contained because of the fact that every element of the hoist has common support on the bedplate, the major ones of said elements being readily separated from the bedplate for piece-meal transportation to virtually inaccessible places.

In the drawings:—

Figure 1 is a side elevation of the improved geared hoist.

Figure 2 is a cross section taken on the line 2—2 of Figure 1.

Figure 3 is a section taken on the line 3—3 of Figure 2.

Figure 4 is an elevation of the left end of the hoist in Figure 1.

Figure 5 is a cross section taken on the line 5—5 of Figure 4.

In working out the details of the instant geared hoist sight has not been lost of the fact that various types and constructions of hoists are in current use for every conceivable purpose to which a hoist may be put. But it has been found that there is an actual need for a hoist which is capable of being disassembled and transported into virtually inaccessible places, and there set up for operation. Such places comprise mines, mountain regions and a large variety of cramped positions in construction works in general. With the foregoing purposes in mind it is a paramount consideration to condense the structural elements to the narrowest possible confines without sacrificing any of the advantages which one could expect of a piece of mechanism of much larger and more complicated proportions.

Reference is made to the drawings. Provision is made of a suitable bedplate generally designated 1. This comprises what is known as fabricated structural steel, or a casting of which the side and cross angles 2, 3 are only the main parts. In practice this bedplate will be braced either with a lattice work of bars or an arrangement of rods which will establish a firm foundation, and yet one of considerable lightness in proportion to its size because of its open-work construction. This bedplate can be mounted on skids if desired. It carries the entire hoist mechanism.

The power plant comprises an electric or other motor 4. This is either mounted on an independent platform 5 (Fig. 1) or directly upon the bedplate 1, as conditions may require. The shaft 6 of the motor projects into the case 7 (Fig. 3) of a reduction unit 8 which contains a train of gearing 9 respectively on the drive shaft 6 and a driven shaft 10 for the purpose of revolving the hoist drum at a low rate as compared with the rate of revolution of the drive shaft 6. The shaft 10 has a pinion 11 affixed to its exposed end.

A pair of end plates or drum supports 12, 13 (Fig. 1) is carried by the bedplate 1 in parallel, upstanding positions. The end plate 12 is secured to a mid cross angle 3 (Fig. 3) by bolts 14 or equivalent means which will serve to hold the plate yet enable its removal for transportation. This plate carries the reduction case 7 which is permanently attached to the end plate 12 by such means as screw studs 15 (Fig. 3). A cover 16

is fitted upon the case 7 and over the studs to which it is secured by nuts which are threaded upon the screw ends of the studs.

Both the case 7 and its cover plate 16 carry suitable bearings (Fig. 3) for the shaft 10. These bearings are of such a type that the shaft 10 will still be adequately supported upon the case 7 and end plate 12 in the event of the removal of the cover plate 16 and the respective bearing. Such a removal will occur when disassembling the hoist for transportation.

The end plate 13 is secured to an end cross angle 3 (Fig. 5) by bolts 17, or equivalent means which will firmly hold the end plate but enable disassembly upon requirement. Each of the end plates 12, 13 has a hole 18 in its upper part to receive the reduced ends 19 (Figs. 3 and 5) of the stationary drum shaft 20. The reductions 19 are only one of a pair of reductions at each end of the shaft, the others, which are larger than 19, being designated 21. These reductions, considered in the order described, form shoulders 22, 23. The reduced ends 19 are threaded at their extremities so that heavy nuts can be screwed on and driven hard against the end plates 12, 13. This sets the end plates firmly against the shoulders 22, and not only holds the shaft 20 stationary but completes an absolutely rigid brace for the hoist drum.

This drum is generally designated 25. It includes a pair of thickened end flanges individually designated 26, 27. These are integral with the drum, either actually or functionally. This means that in small sizes of the hoist the flanges and hub part of the drum will be cast in one piece. In larger sizes the drum and flanges will comprise a fabricated steel construction, that is to say a construction consisting of sections which can be bolted together and unbolted. When they are bolted together the drum constitutes an integral construction as far as function is concerned.

The purpose of thickening each of the two flanges is to utilize the peripheries or outer faces as brake seats. One end of the drum is hollowed out (Fig. 3) so as to provide for an internal gear 28. The teeth of this gear are either cut directly in the drum, or the gear may comprise a ring gear which is set in the hollowed end and permanently secured therein. The pinion 11 meshes with the internal gear, and it is by this means that the drum 25 is driven.

As the drum is driven it revolves on bearings 29 (Figs. 3 and 5). These bearings are interposed between the stationary shaft 20 and drum 25 in any desired manner, and they may comprise either the roller bearings shown or bearings of other types. The inner races 30 on which these bearings run are mounted on the shaft, while the outer races 31 are mounted in recesses 32 in the drum ends. Plates 33 are removably affixed to the drum by means 34 for the triple purpose of retaining the bearings, keeping out dirt and insuring the centralization of the drum 25 on the stationary shaft.

As seen in Figures 3 and 5 the plates 33 are slipped onto the reductions 21 until they almost abut the shoulders 23. In practice there is only enough clearance to prevent binding, and actually there is scarcely perceptible end motion of the drum 25 on the stationary shaft 20 because of the substantial engagement of the plates 33 with the shoulders 23. The drum 25 is therefore kept in the desired central position on the shaft 20, and prevented both from binding against the

pinion 11 and from possibly disordering the operation of the duplex brakes.

These brakes comprise pairs of brake posts 35 (Fig. 2) and 36 (Fig. 4). They are arcuate in shape so as to conform to the end flanges 26, 27 with which they coat. The brake posts have shoes or linings 37 which are engageable with the brake seats, and these linings are capable of replacement when worn. In practice the brake posts are made of fabricated steel. This construction is suggested by the webbing 38 (Fig. 1). The purpose of this construction, as already brought out, is lightness without sacrifice of strength. The web construction is preferable for another reason, namely that the upstanding sides 39, 40 (Fig. 1) of the brake posts can be utilized to house certain essential elements of the operating mechanism.

As concerns the brake posts 35, this mechanism consists of a bellcrank 41 (Fig. 2) which is pivoted between one pair of sides as at 42, and has its remaining pivot 43 connected with an adjustable link 44 which extends across to the companion post between the upstanding sides 39 of which it is pivoted as at 45. The free end of the bellcrank 41 has one end of a rod 46 connected to it, the other end of said rod being pivoted to a pedal 47 which enables the service operation of the brake 35.

By service operation is meant a periodical operation as occurs in stopping and starting. The pedal 45 is pivoted to the bedplate at 48. A spring 49, seated between a stop 50 on the rod 46, and a bracket 51 on the bedplate tends to hold the brake 35 in its released position. The brake is operated against the tension of the spring, and when foot pressure is removed from the pedal the brake automatically assumes its released position.

As concerns the brake posts 36 (Fig. 4), the previously mentioned mechanism consists of blocks 52 which are swivelled at 53 between the upstanding sides 40. These blocks have right and left hand threaded bores which contain the corresponding threads 54, 55 of a brake shaft 56. This shaft carries a handwheel 57, or its equivalent, for the purpose of using hand power to permanently set the brakes 36 upon desiring to fixedly hold the brake drum 25 for any considerable period.

At this point it is desired to state that it is within the province of the invention to equip the pedal 45 (Fig. 2) with a dog of any known type so that it too can be permanently held if desired. However, the showing of the dog is omitted because it is important herein to preserve the distinction between the two brake mechanisms; the one coating with the brake flange 26 being of a temporary service character, the one coating with the brake flange 27 being of a more permanent or locking character. It is desired to state, further, that when the hoist is manufactured in such large sizes that man power cannot be entrusted to working the two braking mechanisms, the pedal 47 and handwheel 57 are intended to be replaced with power-actuated means.

Reverting to the brake posts 35, 36, shouldered bolts 58 (Fig. 1) are used for pivotal mounts. These bolts pass through the end plates 12, 13, and are held in place by nuts 59 on the outside. Brake equalizers can be used in connection with each pair of posts 35, 36, but a brake equalizer is shown only in connection with the posts 36 (Fig. 75).

4). This equalizer comprises a disc 60, or its equivalent, which is turnably mounted at 61 on the end plate 13. At diametrically opposite points this disc has pivot connections 62 for links 63 which extend in opposite directions to places of pivotal connection 64 with the posts 36. As these posts are turned on their pivots 58 the equalizers 60, 63 insure their turning an equal amount, thereby preventing the brake linings 37 from dragging or rubbing on the brake seats.

It is thought that the operation of the hoist is readily understood from the previous description and from an inspection of the drawings. In lieu of a detailed description of the operation it is desired to outline the manner of disassembling the hoist. The nuts 24 are removed from each end of the drum shaft 20. The left end plate 13 is unbolted at 17 from the bed plate 1, and then removed with its attached brake posts 36 and equalizer 60. The drum 25 and its drum shaft assemblage 20 is taken off. The motor 4 is removed, and with it the cover plate 16, the nuts from the screw studs 15 having previously been taken off. The large gear of the train of gearing 9 together with the shaft 10 remain in place on the end plate 12 and in the case 7. Next remove the brake posts 35 from the right end plate 12, and remove the pedal 47 and bracket 51 (Fig. 2) so that the brake posts 35 are clear of the mechanism. Upon removal of the right end plate 12 with its attached reduction unit case 7 the disassembly of the hoist is complete. The several parts can readily be transported to any place which would be inaccessible to the hoist as a whole.

I claim:

1. A readily assembled and disassembled portable hoist of unitary construction comprising a drum which has a pair of integral, thickened end flanges providing brake seats, one end of the drum being hollowed, separate brake mechanisms co-acting with the respective brake seats, one being for service use the other being arranged to lock the drum, a gear located in the hollow of the drum for compactness, a drum shaft and bearing means revolvably supporting the drum on the shaft, a pair of end plates and means by which the shaft is rigidly secured to said plates so as to be stationary, a power plant, a speed reduction unit between the power plant and drum and means by which said unit is attached to one of the end plates, said unit including a pinion in mesh with the internal gear, and a bedplate providing a common support for all elements recited, there being means removably securing the end plates,

brake mechanisms and power plant to the bedplate.

2. A hoist comprising a bedplate, a pair of end plates, means securing the end plates to the bedplate in spaced relationship, said means being separable so that the end plates can be taken down for a piece-meal transporation of the hoist, a speed reduction unit comprising a case and a train of gearing which includes a pinion, means securing the reduction unit to one of the end plates, and a motor to drive the train of gearing, said part of said reduction unit and respective end plate being kept together when removed from the bedplate, a drum shaft and means by which it is affixed to the end plates so as to preserve their spacing and to brace them, a drum and bearings for it on said shaft, said drum having two thickened flanges providing brake surfaces, a gear on the drum in mesh with the pinion for the driving of the drum, duplex brake mechanisms comprising pairs of posts, means by which the posts are mounted on the respective end plates, opening and closing means for one pair of posts and means extending from said means to a pedal carried by the bedplate for intermittent service operation, and means to open and close the other pair of posts, said means being adapted to lock said posts in a fixed braking position.

3. In a hoist, a bedplate, a pair of end plates, means securing the end plates to the bedplate in spaced, upstanding positions, a drum shaft and means by which it is secured to the end plates in a spanning position to hold the shaft stationary and to brace the end plates, a drum, bearings by which the drum is revolvably mounted on the stationary shaft, and means to simultaneously retain the bearings in the drum and to coat with the shaft in substantially preventing end motion of the drum on the shaft.

4. In a hoist, a bedplate, a pair of end plates, means securing the end plates to the bedplate in spaced, upstanding positions, a drum shaft which has two diametrical reductions at each end forming two shoulders at each end, the outermost shoulder abutting the end plates, means drawing said shoulders tightly against the end plates to hold the shaft stationary and to brace the end plates, a drum, bearings by which the drum is revolvably mounted on the shaft, and plates fitted upon the remaining reductions and being secured to the drum so as to come close to the remaining shoulders, thereby substantially preventing end movement of the drum and at the same time retaining the bearings.

FRED P. PORTER.
